(57) **CLAIM**

The ornamental design for a bottle, as shown and described.

DESCRIPTION

FIG. 1 is a perspective view of a bottle showing our new design;

FIG. 2 is a front elevational view of the bottle depicted in FIG. 1, the opposite rear elevational view being identical; FIG. 3 is a side elevational view of the bottle depicted in FIG. 2, representing a partial rotation of the bottle about its vertical center axis from the front elevational view depicted in FIG. 2, the opposite side elevational view being identical; FIG. 4 is a top plan view of the bottle depicted in FIG. 2; and,

FIG. 5 is a bottom plan view of the bottle depicted in FIG. 2.

The broken line environmental showing is for illustrative purposes only and does not form part of the claimed design.
